UNITED STATES PATENT OFFICE.

HENRY ROSENBLATT, OF BROOKLYN, NEW YORK.

DESIGN FOR A FRINGE FOR TRIMMINGS.

Application filed January 15, 1925. Serial No. 12,057. Term of patent 14 years.

To all whom it may concern:

Be it known that I, HENRY ROSENBLATT, a citizen of the United States, residing at No. 522 Autumn Avenue, in the borough of Brooklyn, county of Kings, city and State of New York, have invented a new, original, and ornamental Design for a Fringe for Trimmings, of which the following is a specification, reference being had to the accompanying drawing, forming part thereof.

The figure is a plan view of the fringe showing my new design.

I claim:

The ornamental design for a fringe for trimmings as shown.

HENRY ROSENBLATT.
